LATCHING DEVICE

Jeremiah W. Albin, Babylon, N. Y.

Application August 31, 1940, Serial No. 354,962

12 Claims. (CL 85—5)

The present invention relates to a latching device and particularly relates to a latching device which may be generally applied in connection with the attachment of various sheet metal articles together and more particularly with the attachment of cowls, covers, hoods, and so forth, to mounting structures.

Although not specifically restricted thereto, the present invention may be particularly described in connection with its application to hood or cover locking devices upon automobiles or airplanes in which a cover of metallic or other similar material is to be rigidly attached or locked to a mounting plate or latch structure.

It is among the objects of the present invention to provide a simple locking or latching construction of the character described which will be of inexpensive construction, may be readily operated to make a rigid connection which will not permit of rattling and which may be utilized for long periods of time without damage and without breakage.

In making a locking construction or a latching construction of the character described, it has been found desirable to avoid connections of such a character as might permit play between the plates to be latched or fastened together and it has also been found particularly desirable to avoid resilient connections which would permit swinging of the plates in respect to one another or a separation between the plates by further compression of the spring beyond that which results when the device is latched into position.

It is, therefore, among the further objects of the present invention to provide an improved latching device of the character above described which will give a substantially solid connection between the members, and particularly between the sheet metal articles or plates, to be latched together without danger of play or separation of the plates due to further compression or taking up of the resilient members of the latching device.

Still further objects and advantages will appear from the more detailed description set forth below, it being understood, however, that this more detailed description is given by way of illustration since various changes therein may be made by those skilled in the art without departing from the scope and spirit of the invention.

In accomplishing the above objects, it has been found most satisfactory to provide a key member with a cross bar on one of the plates held in position by a ring on said plate, while the other plate is provided with a cam or wedge construc-

tion which will wedge said cross bar into a recess when it is turned into a locked or latched position.

This cam or wedge construction preferably consists of parallel, oblique wedge members with a central recess at the top of the wedges and with the wedge members being supported upon a flat leaf spring against the plate member carrying the wedge construction.

10 The construction provided should preferably be devoid of coil spring connections and the key and wedge members should be attached to the plates to be connected together without the use of rivets and without piercing the metals other than at the central opening for the key.

By this construction, it is possible to attach both the key and the resilient spring member to the plates to be connected together without riveting and by merely piercing the two plates at the point of connection.

20 Referring to the drawings which illustrate several of the various possible embodiments of the present invention, but to which the present invention is by no means restricted since the drawings are merely by way of illustration and not by way of limitation,

Figure 1 is a top plan view of the locking device of the present invention on a somewhat enlarged scale as compared to actual size showing the back of the device with the key in locked position.

30 Figure 2 is a front view opposite to the view shown in Figure 1.

Figures 3, 4 and 5 are side and sectional views taken on the lines 3—3, 4—4 and 5—5 of Figure 1.

40 Figures 6 and 7 are side perspective views on a somewhat smaller scale as compared to Figures 1 to 5 showing the completed connection with the device in latched position.

Figures 8 to 13 show another embodiment, Figure 8 being a rear view of the locking device in locked position similar to Figure 1; Figure 9 is a rear view of the locking device with the key turned 90° out of position and with the back member removed and Figures 10, 11, 12 and 13 are respectively side and sectional views taken upon the lines 10—10, 11—11, 12—12 and 13—13 of Figure 8.

50 Referring to Figures 1 to 5, the two devices to be attached together may consist of or comprise plate members A and B, the plate member A carrying the key member C and the plate member B carrying the wedge device D which is held in position by the sleeve E.

The key member C is also held in position by a ring F. The wedge member D is resiliently supported upon the flat spring member G.

The ring F is fitted into the bevelled opening 10 in the front plate A (see Figures 4 and 5) which has a reversely bevelled portion 11. The ring has outwardly extending portions 12 and 13 which contact said faces 10 and 11 and are held in position thereby.

The ring F has an interior bevelled face 14 into which fits the bevelled head portion 15 of the key C. The cylindrical opening 16 receives the cylindrical shank or stem 17 of the key C. The end of the key C has the cross pin 18.

The ring F also has a sleeve extension 18a which closely fits within the central opening 19 of the sleeve E. The sleeve E has an outwardly flared head portion 20 which fits into the bevelled opening 21 in the inside plate B. The inside corner of the head portion 20 is relieved, as indicated at 22. The sleeve E has the two lugs 23 form a central boss which abut the central portions 24 of the square leaf spring G.

The ends 25 of the leaf G press up against the connecting ridges 26 of the double wedge member D, which ridges 26 engage the overturned portions 27 of the upwardly extending lugs 28 of the sleeve.

The ridges 26 connect the side elements 29 which are provided with the vertical front or side edges 30 and with the sliding wedge faces 31.

The opposite wedge faces 31 are lower than the non-operative wedge faces 32 and at the peak of the double wedges 31 and 32, recesses 33 are formed for receiving the ends 34 of the cross pin 18.

The pin end portions 34 abut the mounts 35 which constitute the upper portions of the higher wedge faces 32.

In operation, the key C when in a position 90° from the position shown in Figures 1 to 5, is inserted through the opening 19 and between the parallel wedge members constituting the wedge structure D.

It is then turned 90° so that the pin ends 34 will slide up along the oppositely inclined wedge edges 31 to snap into the recesses 33 at the top of the structure D. In this position, the spring end portions 25 will be pressed down into the position indicated in Figure 4 and a firm, rigid connection will be formed between the plates A and B substantially without play and without tendency of the plates to swing toward one another.

Moreover, the spring when stressed in the position shown in Figure 4 will not have substantially any play and there will be no tendency for further stressing or bending of the spring G to take place which will permit movement between the plates A and B and opening therebetween.

In the construction of Figures 2 and 4, the head of the key C is flush with the face of the plate A and has a fillister slot 58.

It will be noted by reference to Figures 3 and 4 that when the lock has been completed the resiliency of the spring G will have been substantially taken up and the spring will be contacting or substantially contacting the end of the plate B and the turned up ends 25a will prevent such spring G from cutting into said plate when it has been fully drawn up, as indicated in Figure 4.

In this position it will be noted also that the

ridges 26 are spaced slightly from the overturned portions 27.

In Figure 6 it will be noted that the plate B' carries an additional plate H which may be welded or otherwise pivotally connected thereto and which is flush with the plate A' and forms an abutment edge at J which enables a more substantial connection between the plates A' and B'.

In Figure 7, on the other hand, the head 152 is elevated above the surface of the plate A² and has a fillister slot 50².

In the construction shown in Figures 8 to 13, (similarly functioning parts being indicated by the same numbers and numerals as in Figures 1 to 5, however provided with a superior "3"), the wedges constituting the element D are curved or may be formed from a tubular member which is recessed or extended at 26³ to permit insertion of the end portions 34³ and the key C³.

It will also be noted in the embodiment of Figures 8 to 13 that the resiliency of the leaf spring G³ has been substantially completely taken up when the two plates are drawn together by means of the key C³.

It is thus apparent that the applicant has provided a simple inexpensive latching construction which may be readily manufactured, assembled and dismantled and will give assurance of a permanent lock when in position.

It is apparent from the specific illustrations shown above that they have been given by way of illustration and not by way of limitation and that the structures above described are subject to wide variation and modification without departing from the scope or intent of the invention, all of which variations and modifications are to be included within the scope of the present invention.

What is claimed is:

1. A fastening device for two parts with openings comprising separate fastening elements, one of said elements consisting of a double wedge element having parallel wedges on opposite sides of said opening mounted on one part, a leaf spring having a central opening supporting said double wedge element upon the part on which it is mounted, the second of said elements being a key having an elongated shank and a cross pin at the end thereof to engage the wedges, said key being so formed as to project inside of said parallel wedges and said cross pin being formed for interlocking engagement with said wedges by the turning movement of the key to detachably fasten said parts together, the resiliency of said leaf spring being substantially taken up upon interlocking engagement between said cross pin and said wedges, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

2. A fastening device for two parts with openings comprising separate fastening elements, one of said elements consisting of a double wedge element having parallel wedges provided with recesses on opposite sides of said opening on one part, a leaf spring having a central opening supporting said double wedge element upon the part on which it is mounted, the second of said elements being a key having an elongated shank

and a cross pin at the end thereof to engage the wedges, said key being so formed as to project inside of said parallel wedges and said cross pin being formed for interlocking engagement with said recesses by the turning movement of the key to detachably fasten said parts together, the resiliency of said leaf spring being substantially completely taken up upon interlocking engagement between said cross pin and said wedges, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

3. A fastening device for two parts having coinciding openings receiving separate coengaging fastening elements respectively associated with the parts to be fastened together, one of said elements consisting of a key and the other of said elements consisting of inclined wedges provided with a leaf spring support, said wedges being positioned on opposite sides of the openings and said key having a cross pin to be moved up over the outside edges of said wedges, and means to connect the ends of said wedges integrally together, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

4. A fastening device for two parts having coinciding openings receiving separate co-engaging fastening elements respectively associated with the parts to be fastened together, one of said elements consisting of a key and the other of said elements consisting of inclined straight wedges provided with a leaf spring support, said wedges being positioned on opposite sides of the openings and said key having a cross pin to be moved up over the outside edges of said wedges, and means to connect the ends of said wedges integrally together, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

5. A fastening device for two parts having coinciding openings receiving separate co-engaging fastening elements respectively associated with the parts to be fastened together, one of said elements consisting of a key and the other of said elements consisting of inclined curved wedges provided with a leaf spring support, said wedges being positioned on opposite sides of the openings and said key having a cross pin moved up over the outside edges of said wedges, and means to connect the ends of said wedges integrally together, said leaf spring being positioned closely parallel to the plate upon which it is mounted and the ends of said leaf spring being bent down toward said plate upon completion of the fastening and latching operation so that the resiliency of said spring has been substantially

all taken up and the fastening and latch formed is a substantially rigid one without further play because of the looseness of the spring.

6. A fastening device comprising separate co-engaging fastening elements respectively associated with the parts to be fastened together, one of said elements consisting of a key and the other of said elements consisting of a double inclined plane structure provided with a leaf spring support, said structure and key being attached to different parts, and being received in openings in said parts to be fastened together to permit said key to be inserted to coact with said structure and to be locked on said structure, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

7. A fastening device comprising separate co-engaging fastening elements respectively associated with the parts to be fastened together, one of said elements consisting of a key and the other of said elements consisting of a double inclined plane structure, said structure and key being attached to different parts, openings being formed in said parts to be fastened together to permit said key to be inserted to coact with said structure and to be locked on said structure, and a leaf spring supporting such structure on the part to which it is attached, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

8. A fastening device for two parts having co-operating openings, said parts carrying a turning key and a leaf spring supported double wedge, the key having portions engaging and locking with the said wedge and taking up the resiliency in said spring, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

9. A latching device for two plates comprising a key on one plate and a leaf spring supported wedge on the other plate, said wedge including two opposite upwardly inclined portions, extending toward each other and circular members to engage said key and wedge and to hold them on their respective plates, said leaf spring being positioned closely parallel to the plate upon which it is mounted and the ends of said leaf spring being bent down toward said plate upon completion of the fastening and latching operation so that the resiliency of said spring has been substantially all taken up and the fastening and latch formed is a substantially rigid one without further play because of the looseness of the spring.

10. A latch construction for two plates having

coinciding openings comprising a key rotatably mounted in one opening and a locking wedge mounted in the other opening, said wedge being provided with a leaf spring support permitting slight movements of the wedge toward and away from the plate on which it is mounted, said key having a cross pin at the end thereof and said wedge being offset from said openings and being provided with an oblique outer edge having a terminal recess over which the pin slides and in which it engages respectively, said leaf spring being positioned closely parallel to the plate upon which it is mounted and the ends of said leaf spring being bent down toward said plate upon completion of the fastening and latching opera- 15

tion so that the resiliency of said spring has been substantially all taken up and the fastening and latch formed is a substantially rigid one without further play because of the looseness of the spring.

5 11. The latch construction of claim 10, said wedge having two parallel elements provided with integral connections.

10 12. The construction of claim 10, said leaf spring being placed upon a central boss extending away from the plate on which the wedge is mounted and to support said wedge a short distance away from said plate.

JEREMIAH W. ALBIN.
